(57) CLAIM

The ornamental design for a fogless mirror, as shown and described.

DESCRIPTION

FIG. 1 is a front isometric view of one embodiment of a fogless mirror showing our new design;

FIG. 2 is a rear isometric view thereof;

FIG. 3 is a top plan view thereof;

FIG. 4 is a front elevational view thereof;

FIG. 5 is a right side elevational view thereof, the left side elevation being identical;

FIG. 6 is a bottom plan view thereof;

FIG. 7 is a rear elevational view thereof; and,

FIG. 8 is a side isometric view thereof.

The broken lines are for illustrative purposes only and form no part of the claimed design.
